RECORD CARD FOR USE IN CARD FILING SYSTEMS

Roscoe L. Van Nostrand, Freeport, N. Y.

Application July 2, 1941, Serial No. 400,847

2 Claims. (Cl. 129—16.5)

This invention relates to record cards for use in a card filing system.

The invention aims to provide, in a manner as hereinafter set forth, a record card being so formed to facilitate the separation, fingering, and shifting thereof, when filed, through the means of the index and second fingers of the hand of a person, and which cannot be accomplished with respect to the forms of record cards now in general use as it is next to impossible to conveniently separate one card of the said forms at a time.

The invention further aims to provide, in a manner as hereinafter set forth, a record card having provisions at its top edge for fitting therein the fingernails of the index and second finger of a hand of a person to thereby facilitate the independent and separate fingering, separating and flipping of one card with respect to an adjacent card, when desired.

The invention further aims to provide, in a manner as hereinafter set forth, a record card having its top edge so formed to thereby provide for a person expeditiously separating and flipping the card with the balls or the fingernails of the index and second fingers when filed separately with respect to other cards arranged adjacent to the card to be flipped.

The invention further aims to provide, in a manner as hereinafter set forth, a set of record cards each of like form and each having its top edge formed with one or more lower parts, and with each succeeding card being oppositely disposed with respect to each preceding card to thereby dispose the lower part or parts of the top edge of a succeeding card in staggered relation with respect to the lower part or parts of the top edge of a preceding card whereby each card is capable of being independently separated and flipped with respect to an adjacent card.

The invention further aims to provide, as hereinafter set forth, a record card having a top edge provided with cutouts for fingering purposes, said card and said cutouts being so constructed that the cards can be staggered with relation to each other, merely by reversing one card face with respect to another.

The invention further aims to provide, in a manner as hereinafter set forth, a record card which is simple in construction, and arrangement, strong, durable, compact, thoroughly efficient in the use intended therefor, independently shiftable and inexpensive to manufacture.

Embodying the aims aforesaid, and others which may hereinafter appear, the invention consists of the novel construction, combination and ar-

rangement of parts as will be more specifically described and illustrated in the accompanying drawing, wherein are shown several embodiments of the invention, but it is to be understood that changes, variations and modifications may be resorted to which fall within the scope of the invention, as claimed.

In the drawing:

Figure 1 is a front elevation of one form of a record card in accordance with this invention,

Figure 2 is a fragmentary view in front elevation showing the arrangement of a preceding card of a set of cards relative to a succeeding card of the set, the same type card being reversed;

Figure 3 is a section on line 3—3 Figure 2.

With reference to Figure 1 a record card, in accordance with this invention, is generally indicated at 11, and it is constructed from any suitable material, preferably fibrous cardboard. The card 11 may be of any suitable contour preferably rectangular and it is so shown. The card 11 will be of the desired length, width and thickness and will consist of a body portion 12 formed with a bottom edge 13, a pair of side edges 14, 15 and a top edge 16. Both faces of the body portion 12 may be ruled or unruled, but preferably such faces will be ruled with a margin at the top thereof. The leading or forward face of the body portion 12 is shown as ruled at 17 and formed with an upper margin portion 17a. The body portion 12 will have its follower or rear face, not shown, ruled and margined in the same manner as the leading forward face thereof.

35 The top edge 16 of the body portion 12 is formed of spaced high parts 18, 19 and 20, and with a pair of spaced low parts 21, 22 cut therein. The low part 22 is arranged between and terminates in the high parts 19, 20. The high parts

40 18, 20 are straight. The high part 19 is of convex curvature. The low parts 21, 22 are of concave form. The high part 18 is of greater length than the high part 20. The high part 19 is of less length than the high part 20. The low parts 21, 22 are of the same length as high part 19, and correspond in length. The high parts 19, 20 are both to the right of the vertical median of body portion 12.

When a series of the cards 11 are arranged in a set 50 or filed, a preceding card 11 will be reversed and thereby oppositely disposed with respect to a succeeding card 11 of the set whereby the low parts 21, 22 of the succeeding card will be disposed in staggered relation with respect to the low parts 22, 21 respectively of a preceding card, and the high

parts 18, 19, 20 of a preceding card will align with the high parts 20, 19 and 18 respectively of a succeeding card. This arrangement provides for the independent handling of a card and for readily separating such card from an adjacent card. The low parts 21, 22 of a card 11 are for fitting the fingernails of the index and second fingers of the hand of a person, or high parts 18, 19, 20 for balls of index and second fingers when shifting the card.

When the cards are in actual use and a file has been made up by the user, every other card of course will be staggered. If it becomes necessary to add an additional card to the file or a dividing or indicating card for any purpose to a previously completed file, such card will line up with either the record card ahead of it or behind it in the file and the staggering effect will be lost. It, therefore, becomes necessary to add a dividing or indicating card and have such dividing or indicating card of a form to preserve the staggering effect of the cards of the file. Such indicating card is indicated at 109, Figure 3, the latter showing a set or file of record cards. The card 109 will conform in contour to the cards of the set with which it is employed, but it is of a different color with respect to the cards of such set, and when in use will have its high and low parts of its top edge oppositely disposed with respect to the record card in front or behind it, whereby the staggering effect of the record cards will be maintained.

Each of the record cards may be provided with an index character, such as A—B, on the front and back of a top edge high part, such as upper right corner, lower corner, etc., and with reference to Figure 2, a preceding record card is formed with a visible index character as at 110. The succeeding card is provided with a visible

index character as at 111. The said characters are disposed in staggered relation.

What I claim is:

1. In a filing system, a record card comprising a body portion having a top edge, a pair of side edges and a bottom edge, said top edge being formed with a pair of concave low edge parts, a convex high edge part and a pair of straight high edge parts, said convex high edge part being located adjacent to one side of the vertical median of said body portion, said straight high parts provided by the end terminal portions of said top edge, one of said low edge parts being disposed between and merging into said convex high edge part and one of said straight edge parts, and the other low edge part being arranged between and merging into the said convex high edge part and the other one of said straight edge parts.
2. In a filing system, a record card comprising a body portion having a top edge, a pair of side edges and a bottom edge, said top edge being formed with a pair of concave low edge parts, a convex high edge part and a pair of straight high edge parts, said convex high edge part being located adjacent to one side of the vertical median of said body portion, said straight high parts provided by the end terminal portions of said top edge, one of said low edge parts being disposed between and merging into said convex high edge part and one of said straight edge parts, and the other low edge part being arranged between and merging into the said convex high edge part and the other one of said straight edge parts, one of said straight edge parts being of greater length than the other, said low edge parts being of corresponding length and of less length than the longest straight edge part and of greater length than the shortest straight edge part.
